G. S. GALLAGHER.

REFRIGERATOR.

APPLICATION FILED JULY 13, 1910.

1,018,180.

Patented Feb. 20, 1912.

UNITED STATES PATENT OFFICE.

GEORGE S. GALLAGHER, OF NEW YORK, N. Y., ASSIGNOR TO EMMA G. GALLAGHER, OF NEW YORK, N. Y.

REFRIGERATOR.

1,018,180.

Specification of Letters Patent. Patented Feb. 20, 1912.

Application filed July 13, 1910. Serial No. 571,695.

To all whom it may concern:

Be it known that I, GEORGE S. GALLAGHER, a citizen of the United States, residing at the borough of Manhattan, in the city, county, and State of New York, have invented an Improvement in Refrigerators, of which the following is a specification.

My invention relates to an improvement in refrigerators in contradistinction to those 10 made of rectangular form of wood and metal lined, or wood and tile lined, or of wood and stone lined and with stationary shelves.

My invention comprises a refrigerator 15 constructed of reinforced concrete, circular or cylindrical in contour, with a reinforced concrete cover with revolving shelves and external means for actuating them, and said shelves preferably subdivided and the refrigerator wall provided with sliding doors 20 for giving access thereto and preferably with means for visually determining where to stop the revolving shelves according to the desired articles placed thereon, all of 25 which is hereinafter more particularly described.

In the drawing, Figure 1 represents in small size the complete refrigerator. Fig. 2 is a vertical section through the same. Fig. 30 3 is a section at the dotted line x, x , of Fig. 2, showing parts in plan. Fig. 4 is a section at about the dotted line y, y , of Fig. 2, also showing parts in plan, and Fig. 5 is a cross section at about the dotted line z, z , of Fig. 2. 35 Figs. 2, 3 and 4 are of large size over Fig. 1 for clearness, and Fig. 5 is of still greater proportions for clearness.

a represents the concrete body of my improved refrigerator. This is preferably circular or cylindrical; is provided with a bottom plate a^1 and support members or legs a^2 . A cover b of reinforced concrete, preferably flat, is advantageously provided with top and bottom metal surfaces and a metal 45 flange to set down around the upper edge of the concrete body. Both the concrete body and the cover are preferably reinforced by a plate b^1 of peculiarly corrugated form which in its identical construction forms the 50 subject of a separate application for Letters Patent filed by me of even date herewith. Near the upper portion of the cylindrical body a I place a platform c preferably of metal as a support for the ice. This platform 55 is preferably slightly dishing toward

the center and at the center is provided with an open-ended thimble or sleeve c^1 . The platform c preferably rests upon a circular annulus rib 2 which is secured to or built into the interior concrete of the refrigerator. 60 Upon the under surface of this platform I provide radial ribs c^2 c^3 , the position of which is shown plainly in Fig. 3. Two of these ribs are preferably solid and securely fastened to the platform and one rib c^2 is 65 partially hollow or tubular, that is, from its outer end near the wall of the refrigerator toward the center, and I provide the refrigerator with several shelves of circular form. These are shown in the drawing at d d^1 and d^2 . 70

The refrigerator is provided with a tubular center e and with radial divisions e^1 preferably equally spaced. These radial divisions are advantageously provided with flanges which are riveted to the tubular center e , and the shelves are advantageously supported by brackets 12 riveted or otherwise secured to the radial divisions and projecting beneath the shelves, so that the center e and the radial divisions are securely 75 fastened as a unit for supporting the shelves. With the said shelves, the radial divisions and the tubular center, I have shown and prefer to employ a top plate f and above and connected to the top-plate f 80 is a circular rack f^1 .

In the radial rib c^2 of the platform c I place a shaft 3, with a gear 4 on its inner end and with a square or other shaped opening 90 in its outer end, and this rib c^2 is cut away at the gear 4 as will appear particularly from reference to Fig. 5.

I provide a sleeve 5 passing through the body of the refrigerator and place in this sleeve an auxiliary shaft 6 on the outer end 95 of which is a handle 7 and on the inner end of which is a reduced squared or other shaped end to pass into the open-end of the shaft 3. These members kept in alinement by their construction insures the platform c 100 against rotation and compels the thimble or sleeve c^1 thereof to become a pivot as it were about which the series of shelves, radial divisions and tubular center turn.

In the bottom of the tubular center e and 105 in the center of the bottom a^1 of the refrigerator I place parts which constitute a step bearing 8 for the series of shelves, divisions and tubular center, and about which and the thimble c^1 said parts turn, and I 110

prefer to employ a drip pipe 9 upon the lower end of the tubular center *e* and a drip cup 10 formed at the center of the bottom plate *a*¹, and a drip pipe 11 from the drip cup 10 and a drip pan 13 below the refrigerator so that all the water from the melting ice passes away by the center thimble *c* or tubular center *e*, drip pipe 9, drip cup 10, drip pipe 11 into the drip pan 13. The 5 teeth of the gear 4 mesh with the teeth of the circular rack *f*¹ and as the handle 7 is turned it rotates an auxiliary shaft 6 and the shaft 3 with its gear 4. This turning movement causes the movement of the circular rack *f*¹ and consequently with it the series 10 of shelves, the tubular center and the radial divisions; all of said parts turning as a unit within the circular body of the refrigerator. In this connection I have provided 15 upon the surface of the refrigerator curved slide-ways 14 and sliding doors *h* which close openings provided in the body of the refrigerator which give access to the several circular shelves, and in these sliding doors 20 25 I prefer to place plates of glass which provide for visually viewing the contents of each of the series of shelves as the same are rotated by the handle 7 and devices actuated thereby. Therefore when it is desired to 30 remove any particular article from the refrigerator, the series of shelves are rotated and the contents of the shelves viewed through the plates or sight-openings *h*¹ and it is only necessary to open any door of the refrigerator when the desired article is found, 35 and also to place articles into the refrigerator.

I have shown in Fig. 3 and may employ, a pan or vessel *i* for holding drinking water 40 inside of the ice chest at the upper end of the refrigerator, with a pipe and cock *i*¹ therefrom and a pan *i*² to hold a tumbler, but I do not limit my invention to the use of these devices, as the same may be dispensed with, and should the vessel *i* be employed it is preferable to make the same conform to the inner contour of the body of 45 the refrigerator.

I claim as my invention:—

- 50 1. A refrigerator comprising a circular or cylindrical body having openings providing access thereto, a bottom plate and supports therefor, a cover adapted to fit over the cylindrical body, a platform near the upper part of the cylindrical body adapted to support ice and form of the upper part of the cylindrical body an ice chest, a series of circular shelves spaced a suitable distance apart, a tubular center and radial divisions connected together and forming a unit adapted to be rotated within the cylindrical body, an open-ended thimble or sleeve depending centrally from the platform for ice and entering the upper open end of the tubular center and forming a

pivot, a step-bearing at the lower end of the tubular center also forming a bearing for the revoluble element and means for rotating the revoluble element and so arranged that a part thereof at the same time fixes 70 the position of the platform for ice.

2. A refrigerator comprising a circular or cylindrical body having openings providing access thereto, a bottom plate and supports therefor, a cover adapted to fit 75 over the cylindrical body, a platform near the upper part of the cylindrical body adapted to support ice and form of the upper part of the cylindrical body an ice chest, a series of circular shelves spaced a 80 suitable distance apart, a tubular center and radial divisions connected together and forming a unit adapted to be rotated within the cylindrical body, an open-ended thimble or sleeve depending centrally from the 85 platform for ice and entering the upper open end of the tubular center and forming a pivot, a step-bearing at the lower end of the tubular center also forming a bearing for the revoluble element, radial ribs on the 90 under surface of the platform for ice for stiffening the same and one of said ribs hollow, a shaft with a gear on one end of the same received in said hollow rib, a sleeve passing through the concrete body of the 95 refrigerator, a shaft in said sleeve and a handle outside on the shaft, means connecting the inner end of said shaft with the end of the shaft in said sleeve for rotating the shafts from the handle, a circular rack secured on the upper end of the revoluble member 100 and adapted to be turned for the turning of the revoluble member by the rotation of the handle.

3. In a refrigerator and in combination, a 105 cylindrical body, a platform for ice near the upper end forming therein an ice chamber, a rib secured to the inner surface of the body as a support for the said platform, a center open-ended thimble or sleeve secured to the under surface of the platform, radial ribs on the under surface of the platform for stiffening the same and one of said ribs made hollow for a portion of its length, a revoluble member within the refrigerator 110 for holding articles to be kept cool, a top plate therefor and a circular rack secured on the top plate concentric with the axis, a shaft in the hollow rib member having a gear on the inner end thereof meshing with 115 the teeth of said rack, and means for actuating said shaft and turning the same to revolve the revoluble member.

4. In a refrigerator and in combination, a 120 cylindrical body, a platform for ice near the upper end forming therein an ice chamber, a rib secured to the inner surface of the body as a support for the said platform, a center open-ended thimble or sleeve secured to the under surface of the platform, radial 130

ribs on the under surface of the platform for stiffening the same and one of said ribs made hollow for a portion of its length, a revoluble member within the refrigerator 5 for holding articles to be kept cool, a top plate therefor and a circular rack secured to the top plate concentric with the axis, a shaft in the hollow rib member having a gear on the inner end thereof meshing with 10 the teeth of said rack, a sleeve passing through the wall of the circular refrigerator body, an auxiliary shaft in said sleeve, a

handle at the outer end of said shaft for turning the same, a connection from the inner end of the shaft to the end of the shaft 15 in said rib, whereby the shaft within the rib is rotated for the rotation of the revoluble body within the refrigerator.

Signed by me this 29th day of June 1910.

GEORGE S. GALLAGHER.
